[57] CLAIM

The ornamental design for an extruded master frame window jamb, as shown and described.

DESCRIPTION

FIG. 1 is a bottom plan view of an extruded master frame window jamb showing my new design;

FIG. 2 is a left side elevational view thereof;

FIG. 3 is a right side elevational view thereof;

FIG. 4 is an end elevational view taken from the top of FIG. 1;

FIG. 5 is a top plan view thereof; and

FIG. 6 is a bottom perspective view thereof.

*Fig. 4.**Fig. 2.**Fig. 1.**Fig. 3.**Fig. 5.**Fig. 6.*
